ABSTRACT

Copying lamps having a filament which is constructed from shorter and longer coil segments which are connected by intermediate members have the drawback that after recrystallisation the intermediate members with the ends of the longer segments have warped. This is avoided by supporting the longer segments at their ends.

ELECTRIC FILAMENT LAMP

The invention relates to an electric filament lamp having a tubular envelope which is sealed by pinches and comprises a filament which extends in the longitudinal direction of the lamp, said filament consisting of a number of helically wound configurations connected by straight intermediate members, the length of the configurations which are present in the proximity of the pinches being larger than the length of the configurations present more in the proximity of the center of the lamp, each of the longer configurations being supported by at least two supports and the shorter configurations by one support, each support comprising a central aperture in which the relevant configuration is present, the outer circumference of said support bearing against the inside of the envelope. Such a filament lamp is known for reproduction purposes. By means of this lamp the possibility is provided of uniformly exposing a surface to be exposed.

In these known filament lamps, the supports which support the longer configurations are present between the center and each of the ends of such a configuration.

In order to give the material of the filament lamp a fibrous structure, the filament is subjected for a few seconds to a current pulse by which the temperature increases due to the resistance, so that the material recrystallises. Because during this operation the filament should extend coaxially in the lamp envelope, which in the case of a horizontal position of the envelope is avoided due to the influence of gravity, the filament is introduced into an electromagnetic field, so that the sagging as a result of gravity is compensated for. It has been found that in the known filament lamps of this type in which the supports which support the longer configurations are present between the center and each of the ends of the configuration, the intermediate members with the ends of the longer configurations present beside the supports have warped after the recrystallisation process.

It is the object of the invention to avoid this drawback. For that purpose, an electric filament lamp according to the invention is characterized in that the supports which are present between the supports adjoining the pinches and which support the longer configurations are provided at the ends of the relevant configurations. As a result of this it is achieved that the longer configurations remain extending coaxially with the lamp envelope throughout their length during the recrystallisation process.

In order that the invention may be readily carried

5 into effect, one embodiment thereof will now be described in greater detail, by way of example, with reference to the accompanying diagrammatic drawing, the sole FIGURE of which shows one embodiment of a filament lamp according to the invention.

The filament lamp comprises a tubular lamp envelope 1 which is sealed at its ends by means of pinches 2. The filament 3 is secured in the pinches by means of foils 4 and consists of the helically wound configurations 5a to 5g, which are connected by means of intermediate members 6. The configurations 5c to 5e, in the centre of the lamp envelope, are shorter than the configurations 5a, b, f, g located on the sides. The short configurations 5c to 5e are supported by the supports 7c to 7e, respectively. The longer configurations 5a, 5b, 5f and 5g are each supported by two supports which are denoted by successively 7a, 7b, 7f and 7g. The supports 7 consist of helically wound pieces of wire which each bear against the inner wall of the lamp envelope with an end portion. In the longer configurations 5a and 5g, present on the side of the pinches 2, the supports 7a and 7g are present between the centre and the end of the configurations facing the adjoining pinch. These supports may, however, also be provided on the said ends of the configurations. According to the invention, the supports 7a, 7b, 7f and 7g are provided at the ends of the associated configurations.

What is claimed is:

1. An electric filament lamp having a tubular envelope which is sealed by pinches comprising a filament which extends in the longitudinal direction of the lamp, said filament consisting of a number of helically wound configurations connected by straight intermediate members, the length of the configurations which are present in the proximity of the pinches being greater than the length of the configurations present in the proximity of the center of the lamp, each of the longer configurations being supported by at least two supports and the shorter configurations by one support, each support comprising a central aperture in which the relevant configuration is present, the outer circumference of said support bearing against the inside of the envelope, wherein the supports which are present between the supports adjoining the pinches and which support the longer configurations are provided at the ends of the relevant configurations.

UNITED STATES PATENT OFFICE
CERTIFICATE OF CORRECTION

Patent No. 3,758,807

Dated September 11, 1973

Inventor(s) Herbert Kamiel Maria OP DE BEECK

It is certified that error appears in the above-identified patent and that said Letters Patent are hereby corrected as shown below:

Col. 1, line 25, "pluse" should read --pulse--.

Signed and sealed this 19th day of February 1974.
